CABINET BATH APPARATUS

George A. Schulte, New York, N. Y., assignor to
Health-Glo Laboratories, Inc., New York, N. Y.,
a corporation of New York

Application April 14, 1938, Serial No. 202,047

2 Claims. (Cl. 219—38)

This invention relates to cabinet bath apparatus, and particularly to improvements in vapor generating units for use in such apparatus.

Cabinet bath apparatus wherein a patient is surrounded by a suitable cover, which confines medicinal or steam vapors generated within the cover to contact with the patient's body, is well known. One form of such apparatus is shown in my Patent, No. 1,932,122, issued October 24, 1933. In general, such cabinet bath apparatus is portable, and is provided with a vaporizing device or unit positioned within the cabinet or cover. Various types of vaporizing units having a burner or heater to produce medicinal or steam vapors have been used.

Heretofore, vaporizing units for use in cabinet bath apparatus have been unsatisfactory in several respects. Such units have been subject to leakage of the medicinal solution or water through numerous seams and joints. Units having the requisite surface area of liquid to be vaporized have been slow to produce vaporization, and have utilized only a small part of the heat applied to them. Another problem has been the failure to rapidly vaporize all of the solution or fluid placed therein. Other problems such as failure to provide for fluid circulation, the danger of electrical shock, and expense of manufacture are well recognized.

It is the object of this invention to provide an improved vapor generating unit having a one-piece pan or receptacle for holding a solution or liquid to be vaporized, and arranged for efficient utilization of heat produced by an electric heating device.

It is also the object of this invention to provide a vapor generating unit in which the exposed surface area of the contained liquid is relatively large with respect to the quantity of liquid, and in which the heater is positioned to efficiently circulate and vaporize all the liquid.

It is another object of this invention to provide a vapor generating unit having a one-piece sheet metal pan or receptacle without seams or openings, whereby leakage of the medicinal solution or water is avoided.

It is another object of this invention to provide an electrically heated vapor generating unit having a heating device arranged in a reentrant portion of the liquid container adjacent to a small relatively confined body of the liquid in said container.

It is another object of this invention to provide a vapor generating unit in which the liquid to be vaporized is caused to flow upwardly through a

relatively small chamber of annular cross section surrounding a heating coil, and then to cascade over the upper edge of a tube defining said chamber.

It is another object of the invention to provide a vapor generating unit which is electrically safe, the heating coil and terminals being fully insulated and protected from the liquid and from the liquid receptacle.

It is the further object of this invention to provide a vapor generating unit of simple and inexpensive construction provided with a curled edge or rim to avoid accidental spillage of the medicinal solution or liquid.

Other objects and advantages of this invention will be readily apparent from the following description of an embodiment of the invention illustrated in the accompanying drawing in which:

Figure 1 is an elevation view in section of a preferred form of my improved vapor generating unit.

Figure 2 is a perspective view showing an arrangement for supporting the vapor generating unit in cabinet bath apparatus.

Referring to Figure 1, for the purposes of illustration, the vapor generating unit is provided with a relatively shallow pan or receptacle, indicated by the numeral 10, containing a medicinal solution or liquid which is to be vaporized. The central portion of the pan 10 is extended downwardly to form a depending well 11, and thence upwardly to form a reentrant portion 12. The reentrant portion 12 may extend approximately to the level of pan 10. The pan 10, including portions 11 and 12, may be constructed from one piece of metal by drawing or spinning.

A shoulder or offset 13 is provided on the reentrant portion 12 for supporting a tubular member 14, which latter surrounds the reentrant portion 12 and extends above the level of the liquid in pan 10. The tubular member 14 may be secured by friction or by welding to the shoulder 13, which spaces it from the wall of the reentrant portion 12. An opening 15 is provided in the lower part of the tubular member 14 to allow fluid to enter the confined space between tube 14 and the reentrant portion 12 of the unit. A resistance element 16 is arranged on a suitable support or core 17, of porcelain or other ceramic material. The resistance element 16 and its core 17 are of suitable size to fit snugly within the reentrant portion 12, and are secured in the reentrant chamber 12 by means of refractory cement 18. The refractory cement 18 conducts heat from the resistance 16 to the reentrant wall 12. Terminal bolts 19

are provided for connecting the ends of the heating element 16 to a supply cable 20. A terminal protecting cap 21, preferably of insulating material, encloses the terminals 19 and may be secured 5 to the base of the coil support 17 by means of one or more nuts and bolts 23. Openings or vents 22 are provided in the terminal cover 21 to prevent the terminals from overheating.

The vapor generating unit 10 may be supported 10 by the leg braces of the stool or chair 5, upon which the patient sits within the usual vapor confining cover or cabinet (not shown). A guard or shield 6 is provided above the vapor generator to prevent the medicinal vapors or 15 steam from overheating the seat of the stool 5.

The operation of my improved vapor generating device is as follows: A medicinal solution or water is placed in the pan 10, covering the entire area thereof. Heat from the element 16 is 20 conducted, by the refractory cement 18 and the wall of the reentrant portion 12 of the pan, to the liquid confined in the annular chamber between the wall 12 and the surrounding tubular member 14. As the body of liquid in said chamber 25 is relatively small, it is quickly heated and thereby caused to rise within the tube 14, and to cascade over the upper edge thereof. Additional liquid enters the annular chamber from the well 11 through the opening 15. As the liquid 30 flows over the upper edge of the member 14, vapors are given off, and the unvaporized hot liquid which falls back into the pan 10 causes agitation and circulation of the fluid in the pan 10 and in the depending well 11. With this arrangement it is possible to vaporize all of the 35 fluid in the pan and nearly all of the fluid in the well 11. The heat produced by the heater 16 is efficiently utilized, since the heating element is almost entirely surrounded by the liquid 40 to be vaporized. The heater 16 and its terminal connections are fully insulated from the metal pan and the liquids therein, and therefore the danger of electrical shock to the patient is eliminated. The curl 24 on the upper edge of 45 the pan 10 prevents the liquid from being spilled, if the pan or stool should inadvertently be tipped or jarred. The pan 10 including the curl 24,

the depending well 11, and the reentrant portion 12 is made of one piece of metal without joints or seams and is therefore leakproof and inexpensive to manufacture.

Obviously, various forms of contacts and heating means may be designed by those skilled in the art, without departing from the scope of this invention which contemplates the use of any equivalent materials and supports, within the 5 terms of the following claims.

I claim:

1. A vapor generating unit for use in cabinet bath apparatus comprising a pan adapted to contain a quantity of liquid to be evaporated, said pan having a depending well portion the 15 bottom of which extends inwardly to form a reentrant portion within said well portion, a baffle member extending above the level of liquid in said pan and into said well portion and having its inner wall spaced from said reentrant portion to form a liquid confining chamber, said member having an opening therein near the bottom of said well admitting liquid from said well into the chamber between said member and said reentrant portion, and heating means 20 mounted within said reentrant portion for heating the liquid in said chamber.

2. A vapor generating unit for use in cabinet bath apparatus comprising a shallow pan adapted to contain a quantity of liquid to be evaporated, said pan having an integral downwardly extending well portion, an integral reentrant portion within said well portion and extending above the bottom level of said pan, and an inwardly curled edge, a tubular baffle member extending from said well portion upwardly above the upper surface of said reentrant portion and above the level of liquid in said pan, said member having its inner wall in juxtaposition to said reentrant portion forming an annular chamber 35 and having an opening therein near the bottom of said well, an electrical heating element positioned within said reentrant portion adjacent said chamber, and enclosed terminal means positioned below said heating element.

GEORGE A. SCHULTE.
